ROADWAY MACHINE

Martin D. Bowen, Savanna, Ill.

Application March 3, 1934, Serial No. 713,874

10 Claims. (Cl. 105—162)

This invention relates to maintenance of way equipment for railroads and has for its principal object to provide a carriage for various mechanical, electrical, or other apparatus that will travel along the track, convenient to the work being done, and readily roll off to clear trains without upsetting or disturbing any of the apparatus carried. The carriages will take various forms according to the apparatus to be carried, which includes motor generator apparatus for welding, grinding machines, rail drills, spike drivers, spike pullers, bolt tighteners, rail joint oilers, ballast tamping machines, etc., some of which are relatively light, while others are very heavy.

Fig. 1 is a perspective view of a roadway machine embodying the invention, and including all the necessary equipment for doing welding along the track;

Fig. 2 is a longitudinal vertical section taken through the axis of the machine shown in Fig. 1;

Fig. 3 is a transverse section taken on the line 3—3 of Fig. 2;

Fig. 4 is an end elevation on a smaller scale, illustrating in a general way the movement of the machine in rolling away from the track to clear a train;

Fig. 5 is a perspective view similar to Fig. 1, but illustrating a lighter form of carriage suitable for much of the apparatus needed by the track crews, and

Fig. 6 is a diagrammatic view illustrating a modification of the form shown in Fig. 1, to avoid distortion where rolling the frame off by power involves a considerable strain.

These illustrations and the corresponding description are used for the purpose of disclosure only, and it will be obvious that the gist of the invention may be embodied in various other forms.

The main frame of the carriage, or machine, includes six channel-shaped side pieces 10, welded to spaced end frames, not unlike wheels, each of which includes a channel 11 bent and welded to form a circular rim which is connected by six channel-shaped spokes 12 welded at their outer ends to the rim and at their inner ends to a tube 13 and two plates 14, which form a sort of hub.

This frame is ordinarily borne on two flanged wheels 15, journaled in bearings 16, fixed to angle pieces 17, bolted to short channels 18, welded between two adjacent side pieces 10 that run along the bottom of the frame.

A short angle 19 is welded to the rim of each

end frame and to a short piece of tubing 20, which forms a socket to receive a tubular guide arm 21 on which is journaled a guide wheel or roller 22. Each guide arm has a hole 23 to receive a spring pressed pin 24, for making the guide arm fast in operative position and permitting it to be readily released to place it on the opposite side of the machine, when the direction of operation is to change.

The apparatus, which the carriage is designed to carry, is mounted on a rectangular bed 25 formed of lengths of channel welded together at the corners. At each end it is welded to the side channels 26, the upper ends of which are welded to a cross channel 27, to form what may be called hangers for the bed. The tube 13, forming the hub body of the end frames, is bored out and fitted with a loose bushing 28, to receive tubular trunnions 29 which extend through the hubs and through short pieces of tubing 30, welded at openings in the cross channels 27 of the hangers. Each trunnion is held in place by three circular clamps 31, which may be set up by bolts 32.

The trunnion 29 at the right in Fig. 2, is longer than the other, and a drum 33 is welded to its outer end.

In the welding machine, here illustrated, the apparatus mounted on the bed 25 includes a six cylinder internal combustion engine 34 developing approximately 50 H. P., and driving a three hundred ampere generator 35 through two universals 36 and a shaft 37. The engine fits directly onto the side pieces of the bed (rubber mounting and the like excluded) but the generator is suspended by its legs 38 from arches 39 formed by pieces of channel welded together and to the sides of the bed 25. One of these arches forms a mounting for a frame 40, carrying the instrument panel, etc., and is in a convenient position for the outlet cables 41 to be led through the hollow trunnion at the right and wound on the drum 33. The hanger at the left, in Figs. 1 and 2, is extended above the trunnion and fitted with straps 42 to support a fuel tank 43.

Each end frame is equipped with a length of cable 44 (Fig. 4) fixed to an eye 45 and a hook 46, adapted to engage one of the rails 47 of the track, when the machine is to be rolled to one side to clear a train.

This operation is well illustrated in Fig. 4, where the solid line position shows the machine upright on the track, and the dotted line position shows it rolled, to the left side, with the cable 44 limiting its movement in that direction.

When the train is past, the machine can be

readily rolled to the right and made to assume its original position, as shown in solid lines. The cable 44 and hook 46 then form a sort of fulcrum to assist in bringing the wheels 15 back to the rail 41.

Other cables 48, fixed to the same eyes 45 and pulled by hand or a suitable windlass, may be used to assist in returning the machine to working position.

10 In such heavy machines as the ones shown in Figs. 1, 2 and 3, and just described, it is also convenient to use the available power for rolling it onto and off the track. This is accomplished here by mounting a 32 volt 1½ H. P. motor 49 (Figs. 1 and 2) on a plate 50, welded to the apparatus bed 25 and connecting the motor with the generator 35 by cables 51.

A double reduction worm gearing 52 is driven by the motor 49 through a belt 53 and drives a pinion 54, meshing with a gear 55, welded to the side pieces 10. As here shown, the gear includes an outer channel hoop 56 and an inner channel hoop 57, fitted with bolts 58, which form the teeth of the gear. The pinion 54 is loose on the shaft 59, and has openings to receive pins 60, carried by a clutch disk 61, keyed to the shaft 59 and shifted back and forth by a collar 62 threaded to the end of the shaft 59.

The reduction gearing is of a commercial form, enclosed within a casing which is bolted on a rectangular frame 63 which, in turn, is bolted to plates 64 welded to the side of the apparatus bed.

Assuming the clutch to be engaged and the engine running, the motor 49 is switched on and drives the pinion 54 which, in effect, causes the swinging apparatus bed to climb up the gear 55 and, in so doing, it causes the main frame to roll in the corresponding direction.

40 Since the motor 19 must be reversed to return the machine to its original position, the reversing switch 65 is mounted on the outer end of the left trunnion 29, in Figs. 1 and 2, and the necessary wires are led through the trunnion.

The clutch is provided for the emergency that would arise should the engine stop, or something else cause a power failure in which case the strength of the entire crew would hardly be sufficient to move the machine unless the pinion 54 could be released.

In making embodiments for other machines the size, shape and general arrangement will, of course, be varied to suit the conditions, but 55 the general features here disclosed are applicable to all. When pneumatic or hydraulic apparatus is on the bed, the hose should be led out through the hollow trunnions, as the cables 41 are in the instant illustration, to avoid injury or tangling when the machine is rolled off or onto the track.

In very heavy machines where the power necessary to roll the main frame is likely to cause a distortion when the single pinion is used, arrangement diagrammatically illustrated in Fig. 65 may be resorted to. In this instance there is a large gear 66 at each end meshing with a pinion 67 on a shaft 68, driven by a motor 69 through reduction gearing 70. Duplicating the drive at each end equalizes the force applied and prevents distortion.

Where the apparatus to be carried is light, a lighter and more wieldy carriage can be made by using tubing instead of channels or other commercial shapes. In such a case the rim of

each end frame is made by bending a tube to form a circular hoop 71, and welding its ends together, then welding the tubular spokes 72 to the rim at their outer ends, and to plates 73 and a tube 74 at their inner ends. The end frames are connected by tubular side pieces 75, two of which are supplemented by wheel frames 76 for the wheels 77.

The apparatus bed 78 is fabricated to suit the conditions and is supported from the tubes 74, 10 as before described.

I claim as my invention:—

1. In a roadway machine, a main frame comprising side pieces connecting spaced end frames, each having a circular loop and braces connecting the loop with a center bearing, flanged wheels aligned lengthwise to the main frame to bear it on a rail, trunnions journaled in the center bearings, one being hollow, hangers depending from the trunnions, an apparatus bed carried by the hangers, apparatus on the bed, and a cable extending from the apparatus through the hollow trunnions.

2. In a roadway machine, a hollow rounded frame, wheels carried in tandem by the frame for engaging one rail of a railroad track and supporting the frame thereon, additional supporting means carried by the frame for stabilizing the machine on the track, and an apparatus bed suspended within the frame for rotating about a horizontal axis relatively to the frame whereby the frame may roll transversely to the plane of the tandem wheels and about the bed.

3. In a roadway machine, a main frame comprising rounded end frames and connecting side pieces, wheels carried in tandem by the frame for engaging one rail of a railroad track and supporting the frame thereon, additional supporting means carried by the frame for stabilizing the machine on the track, an apparatus bed, and means suspending the bed between the end frames for relative rotation about the axis of the end frames.

4. In a roadway machine, a main frame comprising side pieces and spaced end frames connected by the side pieces, each end frame including a substantially circular loop, a central bearing and braces connecting the loop with the bearing, wheels carried in tandem by the frame for engaging one rail of a railroad track and supporting the frame thereon, additional supporting means carried by the frame for stabilizing the machine on the track, an apparatus bed, and hangers suspending the bed from the central bearings.

5. In a roadway machine, a hollow rounded frame, wheels carried in tandem by the frame for engaging one rail of a railroad track and supporting the frame thereon, additional supporting means carried by the frame for stabilizing the machine on the track, an apparatus bed suspended within the frame for relative rotation about a horizontal axis, gearing connecting the bed and frame, and means to drive the gearing to rotate the frame about the bed.

6. In a roadway machine, a main frame comprising rounded end frames and connecting side pieces, wheels carried in tandem by the frame for engaging one rail of a railroad track and supporting the frame thereon, additional supporting means carried by the frame for stabilizing the machine on the track, an apparatus bed, means to swing the bed between the end frames for relative rotation about the axis of the end frames,

and power means to rotate the frame about the bed.

7. In a roadway machine, a hollow rounded frame, wheels carried in tandem by the frame for engaging one rail of a railroad track and supporting the frame thereon, additional supporting means carried by the frame for stabilizing the machine on the track, an apparatus bed suspended within the frame for relative rotation about a horizontal axis whereby the frame may roll transversely to the path of the wheels and about the bed, a reversible motor on the bed, and gearing driven by the motor to rotate the main frame.
- 15 8. In a roadway machine, a main frame comprising side pieces and spaced end frames connected by the side pieces, each end frame including a substantially circular loop, a central bearing and braces connecting the loop with the bearing, wheels carried in tandem by the frame for engaging one rail of a railroad track and supporting the frame thereon, additional supporting means carried by the frame for stabilizing the machine on the track, trunnions journaled in the center bearings, hangers depending from the trunnions, and an apparatus bed carried by the hangers.

9. In a roadway machine, a main frame comprising rounded end frames and connecting side pieces, wheels carried in tandem by the frame for engaging one rail of a railroad track and supporting the frame thereon, additional supporting means carried by the frame for stabilizing the machine on the track, an apparatus bed, means suspending the bed between the end frames for relative rotation about a horizontal axis, an engine on the bed, a generator driven by the engine, 10 a motor receiving current from the generator, and reduction gearing driven by the motor for rotating the main frame about the apparatus bed.

10. In a roadway machine, a main frame comprising side pieces and spaced end frames connected by the side pieces, each end frame including a circular channel, a central bearing, and braces connecting the channel and bearing, wheels carried in tandem by the frame for engaging one rail of a railroad track and supporting the frame thereon, additional supporting means carried by the frame for stabilizing the machine on the track, an apparatus bed, and hangers swinging the bed from the central bearing.

MARTIN D. BOWEN.
